ILLUMINABLE MEMO PAD HOLDER OR SIMILAR ARTICLE

Harry Zelenko, 150 E. 61st St., New York, N.Y. 10021

Filed Dec. 17, 1971, Ser. No. 209,505

Term of patent 7 years

Int. Cl. D19—02

U.S. Cl. D74—1 C

FIG. 1

FIG. 2

FIG. 3

FIG. 4

FIG. 1 is a perspective view of an illuminable memo pad holder, showing my new design;

FIG. 2 is a top plan view thereof;

FIG. 3 is a side elevational view thereof; and

FIG. 4 is a front elevational view thereof.

I claim:

The ornamental design for an illuminable memo pad holder, or similar article, substantially as shown.
